UNITED STATES PATENT OFFICE.

ROBERT E. ANDERSON, OF MORRISVILLE, PENNSYLVANIA, AND DANIEL P. FORST, OF TRENTON, NEW JERSEY, ASSIGNEES TO ROBERTSON ART TILE COMPANY, OF MORRISVILLE, PENNSYLVANIA, A CORPORATION OF NEW JERSEY.

SAGGER.

Application filed March 4, 1927. Serial No. 172,589.

In burning tiles it is necessary to support the same properly spaced apart so that substantially their entire surface shall be exposed to the heated atmosphere. Such tile supports, to all of which the generic name of "sagger" has been applied, have been constructed in different ways, but they are all characterized by the fact that their weight, compared with the weight of the tiles themselves, is considerable. Saggers are usually constructed of refractory material, which may be either vitreous or porous, and, of necessity, they are heated up with the tiles and are cooled down therewith. Inasmuch as the weight of the sagger is usually several times the combined weight of the tiles supported thereby, it will be appreciated that tile-burning, as ordinarily carried on, is very wasteful in that a predominant part of the heat is not usefully expended.

In the burning of tiles by means of heat produced by electricity, which presents some substantial advantages, the necessarily increased cost of heat so generated renders its use almost prohibitive.

In order to make the use of electrically generated heat economically practicable, means must be provided whereby most of the heat will be expended in doing useful work. An important and necessary factor in this economical utilization of heat is a great reduction in the weight of the tile-supporting sagger. This is one of the main objects of the present invention. The object is attained by a sagger, constructed substantially as herein-after described, whose weight may be cut down to a relatively small fractional part of the weight of the tiles supported thereby.

The sagger is particularly adapted and intended for use in a continuous kiln, one preferred form of which is herein shown and described.

In the drawings:

Fig. 1 is a perspective view of a sagger, partly assembled, embodying our invention.

Fig. 2 is a side elevation of two tiers of saggers mounted on a car.

Fig. 3 is a partial cross-section through a kiln, showing the saggers of Fig. 2 in end view.

Fig. 4 is a diagrammatic plan view of a kiln in which our improved sagger is especially adapted for use.

The sagger shown in the drawings com-

prises two upright plates *a*, *a*, rigidly and permanently connected by means of two pairs of bars or pins, one pair of bars *b* connecting the upper parts of the plates and one pair of bars *c* connecting the lower parts of the plates. The bars are permanently secured to the plates and perform the function of providing a unitary structure and of imparting sufficient rigidity to the same to enable it to adequately support the maximum number of tiles which it would be practicable to position between the plates. To enable this maximum number of tiles to be supported, the plates are provided with a series of pairs of orifices, *e*, one pair above another, adapted to receive a series of pairs of bars or pins *d*, one pair above another. Each pair of bars constitutes a shelf on which may be supported a plurality of tiles *x* whose opposite ends overhang the bars. In case of the breakage of one of the removable bars, it may be replaced readily. The pairs of fixed bars and the pairs of removable bars are supported at such distances apart as to leave the desired space for circulation of hot air between the broad faces of the tiles.

The saggers should be so constructed that one may be placed on top of, and be supported by, another. To provide for this, the upper edges of the plates of the lower sagger are provided with longitudinally extending ridges *f* while the lower edges of the plates of the upper sagger are provided with similar complementary ridges *f*. It is preferred to provide such ridges along both the upper and lower edges of the plates of each sagger, so that any sagger may be used as a lower supporting sagger or an upper supported sagger. The saggers, however, may be arranged in a single tier, or they may be arranged in more than two tiers.

The special type of sagger embodying our invention finds its most useful application in connection with a continuous kiln like that shown in the figures. In these figures the kiln *m* is provided with two tracks, arranged side by side, on which cars *n* are adapted to move intermittently in opposite directions. Each car is adapted to carry a number of saggers arranged in longitudinal and lateral rows and in a plurality of tiers. Midway of the kiln the same is provided with lateral offsets *o* in which are located any suitable electric heaters *p*. Thereby the hot zone of the kiln is intermediate the ends and the cold

tiles that have entered the kiln at one end on one track abstract heat from the heated tiles on the other track that will be discharged at the same end of the kiln.

5 It has been found that saggers constructed in accordance with those herein described are adapted to support tiles having a weight (say) of three times the weight of the sagger, instead of, as is usual, being adapted to support (say) one-third their weight of tiles, so that only about one-eighth as much heat is wasted as has been wasted heretofore.

10 Saggers constructed in accordance with our invention are especially adapted, as above stated, for use in electrically heated kilns, wherein the tiles may be left exposed to the heated atmosphere and need not be protected from contact with heated products of combustion. They are also especially adapted for 15 use in electrically heated kilns of the continuous type. In addition to the advantage of light weight, they have the advantage of being adapted to be packed one against another both laterally and longitudinally, thereby 20 utilizing most of the space enclosed in the kilns.

25 The plates should be preferably substantially wider than the tiles intended to be supported between them, and the points of junction of the plates and bars should be preferably a substantial distance from the vertical edges of the plates, so that if the operator fails to place a tile with its center line in precise alignment with the longitudinal center of the 30 sagger, there will be no danger of the edge of a tile carried by one sagger contacting with the edge of a tile carried by a laterally contiguous sagger. The tile-supporting bars should be approximately round in cross-section 35 so that the tiles will contact therewith substantially along a single line, although the bars may be made of other cross-sectional contours.

40 It is preferred to form in the upper edges of the lower plates and in the lower edges of the upper plates, and preferably in both the

45 upper and lower edges of each plate, semi-circular recesses *g*; these recesses being so located that when one sagger is mounted on another, the recesses register and form holes 50 similar to holes *e* and similarly adapted for the reception of removable bars *d*. Thereby it is insured that each sagger of an upper tier 55 will be accurately positioned with relation to the corresponding sagger of a lower tier.

While we have stated that our improved sagger is of especial utility when used in electrically heated kilns, they are also adapted for use with any heating medium and in any type 60 of kiln.

Having now fully described our invention, what we claim and desire to protect by Letters Patent is:

65 1. A sagger for supporting tiles to be burnt, which comprises upright plates spaced apart, a pair of bars spaced apart and rigidly secured to and connecting the plates near their upper edges, a pair of bars spaced apart and rigidly secured to and connecting the plates near their lower edges, and pairs of bars 70 removably secured to the plates between the levels of the upper and lower pairs of bars.

75 2. A sagger for supporting tiles to be burnt, which comprises upright plates each provided with pairs of holes, the holes of a pair being on the same level and spaced from each other and from the upright edges of the plates, one horizontal edge of the sagger being provided with recesses adapted to register with recesses in the horizontal edge of a similar sagger in vertical relationship with the first sagger, bars removably engaging opposite holes in the two plates, and bars whose 80 ends are adapted to removably engage the 85 holes formed by registering recesses when one sagger is superposed on another.

85 In testimony of which invention, we have hereunto set our hands, at Trenton, New Jersey, on this 23rd day of February, 1927.

ROBERT E. ANDERSON.

DANIEL P. FORST.
